UNITED STATES PATENT OFFICE

FRED A. SCHMITZ, OF CANTON, OHIO, ASSIGNOR, BY MESNE ASSIGNMENTS, TO THE BERGER MANUFACTURING COMPANY, OF CANTON, OHIO, A CORPORATION OF NEW JERSEY

CASING FOR BOILERS AND THE LIKE

Application filed December 9, 1927. Serial No. 238,901.

This invention relates to improvements in sheet metal casings or jackets for boilers, radiators, etc., and has for its principal object the provision of a casing which shall be simple in construction, and which may be readily assembled without the use of complicated fastening devices and assembling tools.

Another object of the invention is the provision of a sheet metal casing which will serve to retain in place the coating of heat-insulating material with which boilers are ordinarily provided, and which will present withal a neat and attractive appearance.

These and other objects of the invention will become more readily apparent in the course of the following description of the invention, taken in connection with the accompanying drawings, wherein

Fig. 1 is a front elevation of the casing or jacket;

Fig. 2 is a side elevation of the casing or jacket;

Fig. 3 is a top view of the casing or jacket;

Fig. 4 is a top view of the casing or jacket with the top cover plate removed;

Fig. 5 is an enlarged cross-section taken through one corner of the casing, taken on the line 5—5 of Fig. 1, showing the manner in which the side plates of the casing are secured to the front and rear plates thereof;

Fig. 6 is an enlarged cross-section taken on the line 6—6 of Fig. 3, showing the clip which prevents buckling of the upper portion of the side plate, and which assists in preventing lateral movement of the two sections of the top cover plate of the casing;

Fig. 7 is an enlarged cross-section taken on the line 7—7 of Fig. 3, showing the manner in which the two sections of the top cover plate are secured together.

In the drawings, a cast iron boiler is des-

ignated generally by the letter B, and is provided with various doors 1, 2, 3, 4, and 5, and other appurtenances 6, 7, and 8.

The casing or jacket consists of a front plate 9, a rear plate 10, side plates 11 and 12, and a top cover plate 13, comprising two separable sections 14 and 15, the entire casing being preferably made of smooth finished sheet iron. The spaces 16 and 17 between the sides of the boiler and the side plates 11 and 12, and the space 18 between the top of the boiler and the top cover plate 13, are normally filled with heat insulating material, the casing thereby serving to retain the heat-insulating material in place, and to prevent it from being injured or damaged in any way.

The various parts of the casing are provided with as many openings as are necessary to accommodate the doors and other appurtenances of the boiler, and the top cover plate in particular is provided with a number of circular openings 19 to permit the passage therethrough of various pipes and other conduits with which the boiler is provided.

The front and rear plates 9 and 10 of the casing are provided with beveled marginal portions 20 which terminate in flanges 21 that extend substantially the full length of the plates. These flanges are preferably formed with a straight portion and a reversely bent U-shaped portion 22 which forms seats for the reception of the marginal edges of the side plates 11 and 12, as is clearly shown in Figs. 4 and 5.

By means of the construction described, the side plates are secured to the front and rear plates without the use of bolts or other fastening devices. The frictional engagement of the side plates with the front and rear plates permits a certain degree of movement or adjustment between the various parts, and this is of advantage in that the various parts are thus left free to move

relatively to each other, upon expansion and contraction of the boiler which takes place in ordinary use. Slight variations in the dimensions of the boiler arising in the manufacture thereof are also taken care of in this manner.

The sections 14 and 15 of the top cover plate are provided on one side and at the front and rear with a downwardly turned flange 23 and the contiguous edges 24 of the sections are left unflanged. Each section is provided with a clip 25 which is spot welded or otherwise secured thereto, and which serves a purpose to be presently described.

Secured to the inner face of the front and rear portions of the flange 23 of the section 14, as by spot welding or other means, are short saddle plates 26 which extend beyond the unflanged edge 24 of the section, and the outwardly projecting portions of these saddle plates are provided with apertures 27.

The casing is assembled on the boiler in the following manner:

The doors 1, 2 and 4 and other appurtenances 6, 7 and 8 are first removed from the boiler. The front and rear plates 9 and 10 are then placed in proper position adjacent to the front and rear of the boiler respectively, and the doors are then replaced, the fastening devices which secure the doors to the boiler serving to retain the front and rear plates rigidly in place. The side plates are then slid downwardly in the marginal seats 22 of the front and rear plates as shown in Figs. 4 and 5. Suitably enlarged holes are provided in the side plates so that the devices 6, 7 and 8 may be replaced on the boiler and still permit slidable movement between the side plates and the front and rear plates.

The section 14 of the top cover plate is then placed on the previously assembled parts in such position that the clip 25 will engage in the rear of the side plate 12 in a manner clearly shown in Fig. 6. The other section 15 of the top cover plate is then placed in such position that the clip 25 will engage in the rear of the side plate 11. The clips 25 serve a two-fold purpose. They prevent the side plates 11 and 12 from being bent or forced inwardly in cases where these plates are relatively wide and they also assist in preventing the two sections 14 and 15 of the top cover plate from moving apart laterally.

Bolts 28 are then employed to secure the front and rear portions of the flange 23 of the section 15 to the saddle plates 26 and thereby prevent lateral movement of the two sections of the top cover plate.

It is to be understood that changes may be made in the size or shape of the various parts of the casing without departing from

the scope of the invention as defined in the appended claims.

Claims:

1. In combination with a boiler, a casing including front, rear and side plates; said front and rear plates being rigidly secured to the boiler and said side plates being held in slidable engagement with said front and rear plates for the purpose of permitting limited relative movement between the front and rear plates and the side plates. 70

2. In combination with a boiler, a casing including front, rear and side plates; said front and rear plates being rigidly secured to the boiler and having marginal seats, and said side plates being held in slidable engagement in said seats for the purpose of permitting limited relative movement between the front and rear plates and the side plates. 75

3. In combination with a boiler, a casing including front, rear and side plates; said front and rear plates being rigidly secured to the boiler and having marginal flanges terminating in U-shaped portions, and said side plates being held in slidable engagement in said U-shaped portions for the purpose of permitting limited relative movement between the front and rear plates and the side plates. 80

4. In combination with a boiler provided with devices for securing doors and other appurtenances thereto, a casing including front, rear and side plates; said front and rear plates being rigidly secured to the boiler by means of said devices, and said side plates being held in slidable engagement with said front and rear plates for the purpose of permitting limited relative movement between the front and rear plates and the side plates. 95

5. In combination with a boiler provided with devices for securing doors and other appurtenances thereto, a casing including front, rear and side plates; said front and rear plates being rigidly secured to the boiler by means of said devices and having marginal seats, and said side plates being held in slidable engagement in said seats for the purpose of permitting limited relative movement between the front and rear plates and the side plates. 100

6. In combination with a boiler provided with devices for securing doors and other appurtenances thereto, a casing including front, rear and side plates, said front and rear plates being rigidly secured to the boiler by means of said devices and having marginal flanges terminating in U-shaped portions, and said side plates being held in slidable engagement in said U-shaped portions for the purpose of permitting limited relative movement between the front and rear plates and the side plates. 110

7. In combination with a boiler provided with devices for securing doors and other ap- 115

purtenances thereto, a casing including a plurality of plates surrounding said boiler; certain of said plates being secured to the boiler by means of said devices.

5 8. In combination with a boiler provided with devices for securing doors and other appurtenances thereto, a casing including front and rear plates and side plates surrounding said boiler; said front and rear plates being secured to the boiler by means of said devices.

10 In testimony whereof I affix my signature.
FRED A. SCHMITZ.
